COLLAPSIBLE TUBE AND CAP ASSEMBLY
AND METHOD OF EFFECTING THE SAME

Archibald W. Paull and John A. McGinnis, Wheeling, W. Va., assignors to Wheeling Stamping Company, Wheeling, W. Va., a corporation of West Virginia

Application December 24, 1932
Serial No. 648,816

3 Claims. (Cl. 221—60)

This invention relates to containers and closures therefor, and more particularly to containers formed of extruded soft metal such as are commonly used for tooth paste, shaving cream, 5 and the like, and which are referred to generally as collapsible tubes.

The ordinary collapsible tube comprises an elongated tubular body of a thin flexible nature terminating at one end in a shoulder which has 10 a threaded neck of smaller diameter than the tube projecting therefrom, the shoulder and neck being relatively heavier so as to resist distortion. The neck is externally threaded, and is closed by a cap which is screwed onto the threaded neck 15 and which usually has a cork liner in order to effectively seal the tube. These tubes are usually filled under pressure by filling machines from the end of the tube opposite the capped end, the large end of the tube subsequently being sealed, and 20 it is very important in this filling operation that the cap shall be quite tight, as otherwise the contents of the tube leak out around the cap and spoil not only the appearance of a particular container where the cap is loose, but deposit 25 material on the filling machine which subsequently is transferred to other tubes in the process of filling, necessitating that the machine be stopped. The constituents of such tubes, moreover, are frequently of an extremely oily nature, 30 or other volatile constituents, either of which have to be tightly sealed.

For this reason it has heretofore been considered necessary to provide a cork in the caps for such tubes, this corking operation being a 35 separate manufacturing step in the making of the cap, and the caps have to be tightly screwed onto the tubes in order that the cork will be forced tightly against the end of the tube and prevent leakage.

40 In the formation of such tubes the tube is first extruded from a blank without threads on the exterior of the neck and without the passageway through the neck being open at the end of the tube. The tube is subsequently trimmed to 45 remove metal from the end of the tube to open up the passageway through which end the neck is threaded. According to the present invention, the tube is made in the usual way through the step of trimming and threading the neck.

50 The present invention, however, contemplates the use of a special cap having an outer portion which engages the threaded neck of the tube, and an inner portion which enters the opening in the neck of the tube and is forced by deforming the 55 metal in the neck into a tight sealing relation

with the metal, eliminating any requirement for cork in the cap. Preferably the interior plug is threaded, and the application of the cap to the tube causes a thread to be cut by such plug on the interior of the tube. Since the chasing of the 60 thread on the inside of the neck is effected by the application of the cap to the outside of the tube, the threads on the inside and outside of the neck stay in proper relation to one another, and the use of delicately adjusted machinery for simultaneously chasing the threads on the inside and outside of the neck is eliminated, and there does not have to be any special relation between the point where the thread for that portion of the cap which engages the outside of the neck begins 70 with reference to the point where the thread on the plug portion of the cap begins. Furthermore, by causing the thread on the plug to chase its own thread on the inside of the neck, a closer and more effective sealing is secured than if 75 the thread on the inside of the tube were independently chased.

The invention may be readily understood by reference to the accompanying drawing, in which:

80 Figure 1 represents a longitudinal section of a collapsible tube after it has been extruded and before it has been trimmed or threaded;

Figure 2 is a similar view representing a section through the tube after it has been trimmed 85 and the outside of the neck threaded;

Figure 3 is a view similar to Fig. 2 after the cap has been applied to the tube;

Figure 4 is a view similar to Fig. 3 showing 90 the manner in which the interior of the neck has been threaded by the application of the cap, the cap being removed in Fig. 4; and

Figure 5 is a section through the cap separate 95 from the tube.

Referring to Fig. 5, the cap is of the conventional shape, comprising a body 2 having a laterally projecting flange portion 3 which can be conveniently gripped, and a skirt portion 4 which is internally threaded for application to the threads on the neck of a collapsible tube. Centrally positioned inside the skirt 4, and formed integrally with the body of the cap, is a central plug 5, this plug preferably being shaped in such a way that when the cap is screwed onto the neck of the tube the plug will force itself into 100 seating relation or sealing relation with the soft metal forming the interior of the neck of the tube. Preferably, the plug has external threads 6 for effecting this result. The cap may be formed of the same material as the tube, that is, 105 110

aluminum, or an alloy of tin and antimony, or preferably, it is formed of bakelite or some other material slightly harder than the material of which the tube is formed.

5 Referring to Fig. 1, the collapsible tube is first formed with an extruded thin ductile body 7 having a heavier shoulder portion 8 and a neck portion 9, the end of the passageway through the neck being sealed as indicated at 10.

10 In the usual course of manufacture, which is followed with the present invention, the end of the tube is trimmed to remove the obstruction 10, and a thread 11 is rolled or otherwise chased onto the exterior of the neck. The cap 2 is then applied to the neck. The skirt portion 4 is longer than the plug portion 5, so that the thread on the skirt starts to engage the thread on the neck before the plug enters the passage in the neck of the tube. However, as the cap is screwed home, the plug turning and forcing its way down into the neck of the tube is brought into a tight sealing relation with the interior of the neck of the tube. For instance, by using threads as indicated at 6, these threads cut a shallow thread on the inside of the neck of the tube by means of which a very tight and effective sealing relation between the tube and the cap is brought about, and this sealing relation exists even though the cap should not be turned all the way home on the threaded neck. When the cap is removed, as shown in Fig. 5, the interior of the neck will disclose the shallow thread which has been cut or chased into it by the plug portion 5 of the cap.

35 As hereinbefore indicated, since the thread on the inside of the neck is formed by the application of the cap to the threaded exterior of the tube, the threads on the inside and outside always bear the proper relation with respect to each other and with respect to the threads on the portions 4 and 5 of that particular cap. Moreover, by forming the thread on the inside of the tube by the action of the plug 5, a tighter seal is obtained than if the thread were independently formed on the inside of the neck. By having a cap which is of slightly harder material than the metal of which the tube is formed, a thread is cut into the inside of the neck more effectively than where the plug is of a soft metal and the threads 6 could be mutilated, although our invention contemplates either arrangement. Obviously, also, instead of forming threads on the inside of the neck of the tube, the plug may displace the soft metal of the neck of the tube in other ways to effect a tight seal, although a thread is obviously preferable because of the tighter seal which it effects.

50 As will be seen from the foregoing description, the invention contemplates a new procedure

in the manufacture of collapsible tubes, in that the thread on the inside of the neck is simultaneously effected with the application of the cap to the tube, and the thread on the exterior of the neck provides the lead through which the plug on the interior of the cap cuts the threads in proper relation to the threads on the exterior of the tube.

55 The caps, particularly if formed of bakelite, can be cheaply molded with the threads on them, as will be readily understood by those skilled in the art of working bakelite, and the cap is cheaper to manufacture and requires fewer operations than the ordinary cap now commonly provided in which a cork insert is positioned on the inside of the cap. At the same time, the cap forms a more efficient seal—first, because it does not have to be screwed fully home in order to effectually seal the end of the tube; and secondly, because there is an actual interfitting of the sealing parts of the cap and tube which prevents leakage of the contents of the tube.

90 We claim:

1. The combination with a collapsible tube formed of a soft pliable metal and having an exteriorly threaded neck, of a cap having an interiorly threaded skirt engaging the threaded neck of the tube and having a central plug element of less length than the skirt and adapted to enter the neck of the tube, said plug having threads on the exterior thereof, the diameter of the plug being such that the threads on the exterior thereof will chase threads on the interior of the neck of the tube.

100 2. The combination with a collapsible tube formed of a soft pliable metal and having an exteriorly threaded neck, of a cap of relatively harder material having an interiorly threaded skirt engaging the threaded neck of the tube and having a central plug element thereon adapted to enter the neck of the tube, said central plug being externally threaded and adapted to chase threads on the interior of the neck of the tube when the cap is screwed onto the tube.

110 3. The combination with a collapsible tube formed of a soft pliable metal and having an exteriorly threaded neck, of a cap of relatively harder material having an interiorly threaded skirt engaging the threaded neck of the tube and having a central plug element thereon adapted to enter the neck of the tube, said central plug being externally threaded and adapted to chase threads on the interior of the neck of the tube when the cap is screwed onto the tube, the plug being of less length than the interiorly threaded skirt.
